John O. Cage
INVENTOR
BY Victor J. Evans

ATTORNEY

UNITED STATES PATENT OFFICE.

JOHN ORVILLE CAGE, OF SILVERTON, OREGON.

SANDING DEVICE.

Application filed July 2, 1926. Serial No. 120,176.

This invention relates to a sanding device for motor vehicles, the general object of the invention being to provide means for placing sand on the road surface in front of the 5 drive wheels of the vehicle to prevent the same from skidding and spinning upon said surface.

Another object of the invention is to provide magnetic means for controlling the flow 10 of sand so that the said flow can be controlled by the driver or other occupant of the vehicle.

This invention also consists in certain other features of construction and in the 15 combination and arrangement of the several parts, to be hereinafter fully described, illustrated in the accompanying drawings and specifically pointed out in the appended claim.

20 In describing my invention in detail, reference will be had to the accompanying drawings wherein like characters denote like or corresponding parts throughout the several views, and in which:—

25 Figure 1 is a fragmentary view of a vehicle, showing the invention in use.

Figure 2 is a section on line 2—2 of Figure 3.

30 Figure 3 is a section on line 3—3 of Figure 2.

Figure 4 is a view showing how the valve is operated by the magnetic means.

I prefer to provide means for supplying sand in front of each of the drive wheels of 35 the vehicle. Figure 1 shows a portion of the vehicle at A, with one of its drive wheels at B. A sand receptacle 1 is arranged in the body of the vehicle and has its discharge spout 2 arranged over a nipple 3 which extends through the floor of the vehicle and leads the sand into a chamber 4 formed by a casing 5 which is suitably fastened to the bottom of the floor. This casing is formed with a rounded lower part 6 and a partition 40 7, having holes 8 therein, separates the part 6 from the part 5. Said part 6 has a threaded nipple 9 thereon to which is coupled a pipe 10 which will lead the sand to a point in front of the wheel B. A disk valve 11 is pivoted to the partition 7 and has the 45 holes 12 therein which, when registering

with the holes 8, will permit sand to pass from the upper chamber to the lower chamber, but when said valve has been moved to throw its holes out of register with the holes 55 8, the sand will be held in the upper chamber. An arm 13 is connected with the disk 11 and passes through a hole in the casing and a spring 14 has one end fastened to the arm and its other end to a stationary part 15, 60 said spring tending to hold the parts with the valve in closed position.

An armature 16 of a magnet 17 is fastened to the arm in such a manner that when the magnet is energized, the armature will pull 65 the arm over to a position where the holes in the valve will register with those in the partition so that sand will flow from one chamber to the other and thus be supplied to the road in front of the wheels.

The switch for the magnets could be located adjacent the driver's seat so that the driver could close the circuits to the magnets to cause the sand to flow in front of the 70 wheels whenever desired.

75 It is thought from the foregoing description that the advantages and novel features of my invention will be readily apparent.

I desire it to be understood that I may make changes in the construction and in the 80 combination and arrangement of the several parts, provided that such changes fall within the scope of the appended claim.

What I claim is:—

In a motor vehicle, a sand container arranged therein, a two-part valve chamber supported below the floor of the vehicle, means for connecting the chamber with the bottom of the receptacle, a perforated partition in the valve chamber and arranged at 90 the junction of the two parts thereof, a perforated disk pivotally secured to the partition for controlling the perforations therein, spring means for normally holding the disk in closed position, magnetic means for moving the disk to open position and a pipe connected with the bottom of the valve chamber and extending to a point in front of one of the drive wheels of the vehicle.

95 In testimony whereof I affix my signature.

JOHN ORVILLE CAGE.
